UNITED STATES PATENT OFFICE.

DAVID G. McCAA, OF LANCASTER, PENNSYLVANIA, ASSIGNOR TO THE ELECTRIC APPARATUS CO., OF PARKESBURG, PENNSYLVANIA, A CORPORATION OF PENNSYLVANIA.

RADIO SYSTEM.

Application filed July 18, 1923. Serial No. 652,219.

To all whom it may concern:

Be it known that I, DAVID G. McCAA, a citizen of the United States, residing in Lancaster, county of Lancaster, State of 5 Pennsylvania, have invented new and useful Improvements in Radio Systems, of which the following is a specification.

My invention relates to the reception of high or radio frequency energy, without interference or disturbance due to other high or radio frequency energy produced artificially or by natural electricity, as static, atmospherics, etc., in systems in which the energy is transmitted either through the 10 natural media or over a conductor or conductors extending between transmitting and receiving stations, for purposes of effecting at receiving stations controls, or signals which may be either telegraphic or telephonic.

In accordance with my invention, the frequency of the energy which it is desired should be excluded or reduced in effect and represented by oscillations set up by static, 15 atmospherics or other natural electricity, is caused to differ from the frequency of the energy which it is desired shall be received, and the the undesired oscillations are neutralized by an opposing and substantially 20 equal potential caused by the received undesired oscillations, leaving the desired oscillations to effect the desired signals or controls with no or substantially no disturbance by the undesired oscillations; and prefer- 25 ably the undesired oscillations due to static or other natural electricity are caused to have but a single frequency. And when the undesired high or radio frequency oscillations are artificially produced, as by trans- 30 mitters emitting oscillations of frequency differing from the desired oscillations, their disturbing effects are similarly eliminated or 35 reduced.

Further in accordance with my invention, 40 the desired oscillations, preferably first amplified, are utilized to change the reactance of a circuit or path in which both the desired and undesired signals are received to materially increase the ratio of the ampli- 45 tude of the desired oscillations to the amplitude of the undesired oscillations. Similarly, with regard to undesired oscillations artificially produced and having a frequency

different from the desired oscillations, the desired oscillations, preferably first amplified, effect a change of reactance of a circuit in which both the desired and undesired oscillations are received to render the circuit or path resonant to the desired oscillations and de-tuned or non-resonant with respect to the undesired oscillations. 55

Further in accordance with my invention, a local source of high or radio frequency oscillations, having a frequency differing from the desired oscillations, is utilized to 60 effect a variation of reactance whereby the desired oscillations are caused to partake of maximum amplitude in a certain part or branch of said circuit or path and thereby increase the ratio of the effect of the desired oscillations to the effect of the undesired oscillations in the ultimate translating device or signal-translating instrument. 65 And in case the desired energy is that of undamped waves, the oscillations produced by the local source serve in addition to effect, for telegraphy, periodic variation in the combined effects of the locally produced oscillations and the desired oscillations to thereby produce an audible signal. 70

My invention resides in the method and apparatus of the character hereinafter described.

For an understanding of my method, and for an illustration of some of the various forms my apparatus may take, reference is to be had to the accompanying drawings, in which:

Fig. 1 is a diagrammatic view of radio receiving apparatus embodying my invention.

Figs. 1^a and 1^b are diagrammatic views of modifications of the system shown in Fig. 1.

Fig. 2 is a diagrammatic view of apparatus in accordance with my invention in which the absorption structure is in the form of a loop aerial or antenna, and in which the desired oscillations operate more directly upon the receiving circuit or path.

Figs. 3, 4 and 5 are diagrammatic views of further modifications.

Fig. 6 is a diagrammatic view of further modifications of my invention relating in part to telegraphy.

Referring to Fig. 1, A represents generally any absorption structure of a radio

receiving system, as an antenna, or frame or loop aerial, of the character indicated in Fig. 2, or any equivalent of either of them, or any combination of them; A represents 5 also a conductor system extending between the transmitting and receiving stations as in the case of high frequency or carrier wave conductor systems. For brevity, however, the invention will be described in connection 10 with radio receiving systems utilized either for effecting a control or controls of any character, as for controlling movements of ships or aircraft, picture or motion picture apparatus, or signaling apparatus in general, including telegraphic and telephonic apparatus, it being understood that the translating instrument T hereinafter referred to may be a signal-translating instrument, as a telephone, or any other translating instrument for effecting any suitable control.

In the path between the antenna A and earth or counter-capacity E are included the variable tuning condenser C, which may be 25 omitted if suitable or desirable, the primary P of an oscillation transformer preferably variably coupled to its secondary S, and the inductance L.

In circuit with the secondary S are the 30 variable tuning inductance L¹ and condenser C¹, switch s and variable inductance L², in shunt to which latter are serially connected the variable tuning condenser C² and variable tuning inductance L³, to whose terminals is connected the grid circuit of a detector of any suitable character, preferably a thermionic detector V of the audion type comprising anode p, grid g and filament or cathode f. In the connection to the grid 35 is included the fixed condenser C³, shunted by a grid leak resistance r, as commonly employed in connection with audion detector tubes. In the anode or plate circuit is the source of current or battery B and the translating instrument T, as a telephone, and the driver coil or winding D of an oscillation 40 transformer whose secondary F is connected through the switch s¹ in parallel with the inductance L. Inasmuch as the detector tube V as employed in this example of my 45 invention is utilized also as a radio frequency amplifier, the battery B and transformer T are preferably shunted by a radio frequency by-pass condenser C⁴. The circuits S, L¹, C¹, L² and L², C², L³ have 50 a common connection a to earth or counter-capacity E. X in the absorption circuit or antenna path A represents a point of relatively high potential, and preferably coincides approximately with a point of potential anti-node. That is to say, X is preferably a point in the electrical length of the 55 antenna path above the earth or counter-capacity E at which exists a high potential or anti-node of potential. The point X is

connected through the preferably variable condenser C⁵ with a point Y common to the two circuits S, L¹, C¹, L² and L², C², L³. The mode of operation is as follows:

Assuming first that the windings D and 70 F are omitted, or are not functioning, as when the switch s¹ is open, the antenna path is attuned, when the switch s is open, to the frequency of the oscillations representing the desired signal or control by suitably adjusting C, P, L, or any two or more of them; and the circuit L², C², L³ is similarly attuned to the frequency of the oscillations of the desired signal or control, as by adjusting L², C² 75 or L³, or any two or more of them. Thereafter, the antenna path is de-tuned with respect to the frequency of the desired oscillations, as by adjusting C, P, L, or any two or more of them. Thereupon the switch s is closed, and the circuit S, L¹, C¹, L² is 80 attuned to the now period of the antenna path by varying L¹, or C¹, or both, leaving L² as previously adjusted when tuning the circuit L², C², L³ to the frequency of the 85 desired oscillations.

Assuming that during the reception of signals there exists a natural atmospheric disturbance, as static, strays atmospherics, etc., there will be set up in the antenna path 90 oscillations of a frequency determined by the natural period of the antenna path, and that frequency will be either higher or lower than the frequency of the oscillations representing the desired signal or control. Energy represented by the oscillations of frequency different from the signal frequency will be transferred through the coupling PS into the circuit of the secondary S, which has been attuned to the frequency of the undesired oscillations, and there then exists across the terminals of the inductance L² an electro-motive-force dependent upon the amplitude of the undesired oscillations in the circuit of the secondary S, and such electro-motive-force affects 100 the grid circuit of the tube V, and therefore the translating instrument T. But by connecting the points X and Y directly, as when condenser C⁵ is omitted, these points are closely coupled, and there is impressed across the terminals of the inductance L² an electro-motive-force of such magnitude and in such phase relation with respect to the undesired oscillations in the circuit of the secondary S that the electro-motive-force so impressed by the coupling more or less completely opposes the electro-motive-force across the terminals of the inductance L² due to the oscillations in the circuit of the secondary S, with the result that the 110 effect of the undesired oscillations upon the grid circuit of the tube V, and therefore upon the instrument T, is reduced. However, it is desirable that the coupling between the points X and Y be a more or 115

less loose coupling, and variable, and for this purpose the variable condenser C^5 is employed, with the result that by adjustment of the capacity of the condenser C^5 the 5 electro-motive-force impressed by the coupling therethrough across the terminals of the inductance L^2 may be made equal and opposite to the electro-motive-force existing across the terminals of the inductance L^2 due to the oscillations of undesired frequency in the circuit of the secondary S . The result is that there is not impressed 10 upon the circuit L^2 , C^2 , C^3 , and therefore not upon the grid circuit of the tube V , any 15 effect due to the oscillations of undesired frequency which, as stated, are due to static or other natural atmospheric disturbances, and the result is that the signal-translating instrument T is practically completely 20 shielded from the effects of undesired oscillations. For the purpose described it is desirable that the electro-motive-force impressed across the terminals of the inductance L^2 , through the coupling C^5 shall be in 25 opposite phase to and substantially equal in amplitude to the electro-motive-force existing across the terminals of the inductance L^2 due to the oscillations of undesired frequency in the circuit of the secondary S . 30 The adjustment of the condenser C^5 controls the amplitude of the electro-motive-force impressed by the coupling, while variation of the coupling between the primary P and secondary S determines the 35 amplitude of the electro-motive-force across the terminals of the inductance L^2 due to the oscillations in the circuit of the secondary S . Therefore, by suitably varying the coupling of PS and the capacity of the 40 condenser C^5 , or both, the desired optimum adjustment for the purposes described is effected. Furthermore, as regards phase 45 relations, the sense of coupling as between P and S is of importance, and this sense of coupling is readily reversible to procure the end sought either by reversing the sense of connection of either P or S in its circuit, or when the coils P and S are relatively 50 rotatable with respect to each other one of them may be rotated to such position that the sense of coupling is reversed and made suitable for the purposes described. The 55 electro-motive-force at the point X is ninety degrees out of phase with the current in the antenna path; and the electro-motive-force in the circuit of the secondary S is to similar extent out of phase with the current in the circuit of the primary P , and accordingly, 60 by properly choosing the sense of coupling between P and S the aforesaid phase relations suitable for the result described are readily obtainable.

With the effect of the undesired oscillations upon the detector V and instrument T reduced or eliminated as described, a very

large proportion of the energy of the oscillations of the desired signal or control existing in the antenna path, and of frequency different from the frequency of the oscillations in the circuit of the secondary S , passes 70 by way of the coupling X , C^5 , Y , inductance L^2 and connection a to the earth or counter-capacity E , setting up an electro-motive-force of corresponding frequency across the terminals of the inductance L^2 and therefore 75 impressed upon the circuit L^2 , C^2 , L^3 attuned to the frequency of the desired signal or control oscillations, and accordingly affect the tube V and through it the signal-translating instrument T , whereby the desired signal or control oscillations affect the signal-translating device T with little or no disturbance by the undesired oscillations. Inasmuch as the circuit of the secondary S is de-tuned with respect to the frequency of 80 the desired signal or control oscillations, there is practically no energy representing the desired signal or control in the circuit of the secondary S .

It will be understood concerning the foregoing description of operation that the desired signals or controls may be represented either by trains of decadent waves, such as emitted by a spark transmitter, or may be non-decadent or sustained or undamped 95 waves, as in telephony.

Assuming that when the energy of the desired signal or control is being received there exist in the natural media or are otherwise impressed upon the path of the antenna A oscillations of frequency differing from the frequency of the oscillations representing the desired signal or control, the same results are attained, but in such event the antenna path and the circuit of the secondary 100 S are attuned to the frequency of the undesired oscillations.

While in the operation above described the antenna circuit or path is de-tuned as regards the desired signal or control waves, 110 it may be left attuned to the frequency of the desired signal or control waves, and the circuit of the secondary S is then attuned to a frequency different from the frequency 115 of the waves of the desired signal or control, and therefore different also from the now equal frequency of the waves due to static or other atmospheric disturbance. In this event, the advantages of my invention are nevertheless to considerable extent realized, because the oscillations due to static or the like are often or generally in the form of highly decadent waves, and therefore a large proportion of the energy of the decadent waves will nevertheless appear in the 120 circuit of the secondary S , and their effect, as upon the grid circuit of the tube V , is reduced or eliminated by the coupling effected between the points X and Y . The circuit of the secondary S being de-tuned with re- 125

spect to the frequency of the waves representing the desired signal or control will be but very slightly, if at all, affected by the signal or control energy, and therefore, 5 the circuit of the secondary S operates to absorb practically no signal or control energy, but absorbs a relatively large proportion of the energy due to static or the like and represented by the decadent waves.

10 The arrangement first above described is by itself of great advantage, notwithstanding the fact that the antenna path is detuned with respect to the frequency of the desired signal or control waves, with the 15 result that the oscillations representing the desired signal or control are of lesser amplitude than if the antenna path were attuned to their frequency.

The aforesaid disadvantage may be 20 largely or wholly overcome, however, by recourse to the windings D and F. With the switches s and s^1 open, the antenna path is attuned to the frequency of the desired signal or control oscillations, and the 25 circuit L^2 , C^2 , L^3 is attuned to the same frequency. The switch s^1 is then closed, thereby bringing the winding F into parallel with the winding L, the inductance of the winding F preferably being considerably smaller than the inductance of L. With the inductance of F in parallel to the inductance L, the antenna path is now detuned to the signal frequency, and the frequency of the oscillations due to static or the 30 like is higher than the signal frequency. At the point X, then, there exist electro-motive-forces of signal frequency and of a higher frequency, and by virtue of the coupling from X to Y these electro-motive-forces 35 are impressed across the terminals of the inductance L, the electro-motive-force of signal frequency relatively greatly affecting the potential of the grid g of the tube V, while the electro-motive-force of higher 40 frequency due to static influences the grid g to far lesser degree. The signal-representing oscillations are not only detected by the tube V, but are also amplified, and there accordingly traverses the winding D a current 45 having radio frequency equal to the signal frequency. With proper sense of coupling between D and F, D will cause by induction across the terminals of the inductance F an electro-motive-force of such magnitude, as may be determined by the degree of 50 coupling, and in such direction, due to the sense of coupling, that current of signal frequency will be excluded from the winding F, the effect being the same as if the 55 inductance of the coil F were greatly increased, and the degree of change of the inductance of the winding F as influenced by the current in the winding D may be 60 or preferably is made such that while current of signal frequency is traversing the

winding D, the antenna path is again tuned to the signal frequency, with the result that through the coupling X and Y the effect of signal frequency upon the grid g is enhanced, with correspondingly greater response by or in the telephone T. 70

By use of the arrangement such as D, F, the period of the antenna path differing from the period of the signal oscillations is caused to become equal to the period of the signal oscillations. It will be understood, however, that, in general, by reversing the sense of coupling between D and F, the reverse effect may be obtained, that is to say, the inductance of F may be decreased, and 80 correspondingly changing the natural period of the antenna path.

In the last above description, the circuit of the secondary S has not been utilized, and some of the energy of oscillations due 85 to static finds its way into the circuit L^2 , C^2 , L^3 , and may have some effect upon the instrument T. But this effect may be reduced or eliminated by closing the switch s and tuning the circuit of the secondary 90 S to the aforesaid higher frequency of the oscillations due to static, whereupon the potential difference between the terminals of the inductance L^2 due to the frequency of the undesired oscillations is counteracted by 95 the substantially equal and opposite potential impressed thereon by the coupling X, Y, and accordingly there is substantially no effect upon the grid g, and therefore upon the instrument T, due to static. Under 100 these circumstances, the current in the coil D is entirely that due to or representing the signal, and, as aforesaid, no current of signal frequency is admitted to the coil F, and the period of the antenna path is restored to equality or substantial equality 105 with the frequency of the signal, as above described. Under these circumstances, a greater portion of the static in the antenna path passes to the earth or counter-capacity E through the coil F, in so far as it is permitted to flow through coil F by the current of signal frequency traversing the coil D. 110

Such feeble energy of oscillations due to static as may be transferred from coil F 115 to coil D and thence through the capacity existing between the anode p and grid g is counteracted by the potential existing across the terminals of the inductance L^2 as imposed thereon by the coupling X, Y and the circuit of the secondary S. 120

The operation involving the use of the coil D or coil F and circuit of the secondary S above described is the same when the disturbing effect is that of undamped or damped waves impressed upon the antenna path and having a frequency differing from the signal frequency. 125

The arrangement of Fig. 1^a is in general the same as that of Fig. 1. However, 130

in lieu of the inductance L^2 of Fig. 1, serving as a magnetic or auto-transformer coupling between the circuit of the secondary S and the circuit L^2 , C^2 , L^3 , there is employed a variable coupling capacity C^6 , whereby the circuits S^2 , L^1 , C^1 , C^6 , and C^3 , C^2 , L^3 are electro-statically coupled.

In Fig. 1^b the arrangement is in general similar to that of Fig. 1^a, except that the condenser C^1 of Fig. 1^a is omitted, with the result that the coupling between the circuits S , L^1 , C^6 and C^3 , C^2 , L^3 is closer or tighter than in the arrangement of Fig. 1^a.

It will be understood that in the arrangements above described there may precede the detector V one or more stages of radio frequency amplifiers, and that the winding D may be in the anode circuit of any one of them or may remain in the anode circuit of the tube V . It will further be understood that in place of the translating instruments T there may be inserted the primary of an audio frequency transformer whose secondary controls the potential of the grid of an audio frequency amplifier, the number of stages of audio frequency amplification being multiplied, if desired, and the signal or control instrument T will be connected in the anode circuit of the last stage.

Referring to Fig. 2, in lieu of an open or ordinary aerial or antenna the absorption structure comprises the stationary or rotatable frame or loop aerial G of one or more turns and of suitable area in closed circuit with which are included the variable tuning condenser C , primary P and inductance or oscillation transformer secondary S^1 . Here again between the points X and Y is the coupling condenser C^5 , through which there is effected a coupling which again balances across the terminals of the inductance L^2 the potential differences due to the oscillations of undesired frequency. In this example of my invention, the coil D , in the anode circuit of the amplifier or detector-amplifier V , is traversed by current solely or predominately of signal frequency, having the effect upon the inductance or secondary S^1 to change the inductance of the closed circuit including the loop G as described in connection with Fig. 1, the closed circuit including the loop G during normal operating being de-tuned with respect to the signal frequency and being brought back into tune with the signal frequency by the increase of the inductance of S^1 when the coil D is traversed by current of signal frequency; or by reversal of coupling between D and S^1 , as described in Fig. 1, the inductance of S^1 may be decreased, bringing the closed circuit including loop G back into tune with the signal frequency if it had previously been de-tuned to lower frequency.

The operation is improved by connecting a suitable point of the closed circuit to earth or counter-capacity E , as by closing the switch s^3 . It is desirable also to connect one terminal of the inductance L^2 to earth or counter-capacity E , as by closing the switch s^4 . Either or both of the switches s^3 or s^4 may be employed simultaneously, or both connections to earth E may be omitted when the capacity of the parts and connections with respect to earth is suitably large.

Referring to Fig. 3, there is disclosed a modified arrangement in which the circuit L^3 , C^2 is coupled to the point X through the condenser C^5 and an additional condenser C^7 , which may be fixed or variable, the circuit L^3 , C^2 being connected to earth or counter-capacity E through the connection a^1 .

With the switch s open, the antenna path is attuned, as by variable inductance L^4 , or any equivalent means, to the signal frequency, to facilitate tuning of the circuit L^3 , C^2 to the signal frequency. The antenna path is then de-tuned, as by either increasing or decreasing the inductance L^4 , thereby either reducing or increasing the frequency of the oscillations which will be set up by static or the like. Then the switch s is closed and the circuit S , L^1 , C^6 is attuned to the now natural frequency of the antenna path, and the natural period of the secondary S accordingly is equal to the period of the oscillations due to static. By suitably adjusting the condenser C^6 , and the degree of coupling between P and S , and with proper sense of coupling between P and S , the electro-motive-force at the terminals of the condensers C^6 due to the oscillations of undesired frequency in the circuit of the secondary S is neutralized by the electro-motive-force of the same frequency impressed upon the terminals of the condensers C^6 through the coupling between X and Y . Accordingly, the oscillations of undesired frequency have no effect upon the circuit L^3 , C^2 , and therefore no effect upon the grid of the radio frequency amplifier V^1 , whose plate circuit is coupled to the grid circuit of the detector V . The circuit of the secondary S being attuned to the undesired frequency, little or no energy of the desired frequency is present in that circuit, and substantially all of the energy of signal frequency is impressed upon the circuit L^3 , C^2 through the coupling capacities C^5 , C^7 .

The advantage as regards reduction of static effects will be to lesser degree obtainable if the antenna path remains tuned to the signal frequency, in which case the circuit of the secondary S , remaining de-tuned to signal frequency, will admit very little energy of signal frequency, but rel-

atively greater proportion of the energy of the oscillations due to static, and the electro-motive-force across the condenser C^6 due to the predominant or greater energy due to static will be annulled, due to coupling between X and Y, and the signal frequency will predominate in effect upon the circuit L^3, C^2 , which will be affected to far lesser degree by the oscillations due to static. By recourse to the amplifier V^1 , or more of them in advance of the detector V, the signal energy which is of lesser amplitude when the antenna path is utilized in the condition in which it is de-tuned with respect to the signal frequency is compensated for by amplification.

The arrangement of Fig. 3 operates similarly when the disturbing effect is that of undamped or damped waves of other signals impressed upon the antenna path.

In order to maintain the point Y at suitably high potential, the circuit of the secondary S is connected to earth or counter-capacity E through the connection a , in which is included a fixed or variable condenser C^8 . By maintaining the potential of the point Y higher, as effected by the condenser C^8 , there is transferred to the circuit L^3, C^2 a relatively greater proportion of the received signal energy.

The arrangement of Fig. 4 is similar to that of Fig. 3, except that between the point Y and the upper terminal of the condenser C^6 there is included an additional fixed or variable condenser C^9 when the switch s^2 is closed. The condenser C^9 in a measure combines the functions of the condensers C^7 and C^8 of Fig. 3, in that it loosens the coupling between the upper terminal of the condenser C^6 and the upper terminal of the inductance L^3 , and in that it also serves to maintain the potential of the point Y higher. By this arrangement there is only one coupling capacity, namely, C^6 , between the point X and the upper terminal of the inductance L^3 . This circuit arrangement is employed in general as described in connection with Fig. 3. Here again the antenna path and the circuit L^3, C^2 are attuned to the signal frequency, whereupon the antenna is de-tuned, the circuit of the secondary S attuned to the now period of the antenna, and the switch s^2 then closed. The operation is in general, both for artificial and natural disturbances, substantially that described in connection with Fig. 3.

Referring to Fig. 5, the arrangement is in some respects similar to that shown in Fig. 4, particularly as regards the employment of the condenser C^9 . In this case, however, the grid g of the amplifier V^1 is connected directly to the point Y, and the coupling between X and Y is effected through a variable inductive or non-inductive resistance R in lieu of the condenser C^6

of the preceding figures, it being understood that when suitable or desirable the resistance R may be used in the arrangements of each of the other figures in lieu of the condenser C^6 .

Referring to Fig. 6, there is in the antenna path the tuning inductance L^4 , the primary P^2 and the primary P. Variably coupled to the primary P^2 is the secondary S^2 , in circuit with which is the variable tuning inductance L^5 and variable tuning capacity C^{10} , a connection to earth or counter-capacity E being made through a^2 . Between the points X and Y is again employed the coupling capacity C^5 , which may be connected either through the switch s^5 or s^6 to a point between secondary S^2 and inductance L^5 , or to a point between inductance L^5 and condenser C^{10} , the connection through switch s^5 being preferred. The grid circuit of the detector V is connected across the terminals of the condenser C^{10} . The potential of the point X is carried directly to the point X^1 through which it is impressed, when the switch s^7 is closed, through the variable condenser C^9 to one terminal of the condenser C^6 in the circuit of the secondary S. The other terminal of the condenser C^6 communicates through the connection a with earth or counter-capacity E and inductance L^3 , which with the tuning condenser C^2 is attuned to the signal frequency which is impressed upon the grid g of the radio frequency amplifier V^1 , which may be utilized alone or may be supplanted by several stages of radio frequency amplification.

In the plate circuit of tube V^1 , or in the plate circuit of the last amplifier, when there is a series of radio frequency amplifiers, is the driver coil D, functioning similarly to driver coil D of Fig. 1, when the switch s^8 is thrown to the left.

The antenna path is first tuned to the signal frequency, neither switch s^5 nor s^6 being closed, and switches s^7 and s being open, to facilitate tuning of the circuit S^2, L^5, C^{10} to the signal frequency. The switch s^9 is now closed, bringing the inductance or secondary F into parallel with the primary P^2 , the inductance of which latter is preferably materially greater than the inductance of F. This de-tunes the antenna with respect to the signal frequency, and, as hereinbefore described, the signal energy appears as forced oscillations while the oscillations due to static are free oscillations. The coil F being of lesser inductance than the primary P^2 and being in parallel therewith, the greater proportion of the energies of the oscillations representing signal and due to static flow by the branch F to earth E, and there appears in the circuit of the secondary S^2 greatly reduced oscillations representing signal and due to static. There result cor-

respondingly feeble electro-motive-forces of signal and undesired frequencies across the terminals of the condenser C^{10} , and these are neutralized, when either of the switches s^5 5 or s^6 is closed, by suitably adjusting the condenser C^5 . Under these circumstances, the grid g of the detector V is not influenced by either of the signal-representing oscillations nor the oscillations due to static, and there 10 is no effect upon or in the instrument T .

Now the switch s^7 is closed, whereby the potential at the point X^1 , equal to the potential at the point X , is impressed across the condensers C^9 , C^6 and inductance L^3 through 15 the connection a to earth or counter-capacity E , and the circuit L^3 , C^2 being attuned to signal frequency, there flows into the driver coil D an amplified current of signal frequency which increases, as hereinbefore described, 20 the impedance of the coil F , thereby causing transfer into the circuit of the secondary S^2 , tuned to signal frequency, of energy of signal frequency, greatly predominating over the energy of undesired 25 frequency in the circuit of the secondary S^2 , with the result that the grid of the tube V is subjected to potential variations at signal frequency, causing the instrument T to respond to the signal energy and to be affected only in slight degree by the energy 30 of undesired frequency. The operation may be improved, however, by closing the switch s , whereupon the circuit S , L^1 , C^9 , attuned to the undesired frequency, is traversed by 35 current of undesired frequency causing across the terminals of the condenser C^9 an electro-motive-force of the undesired frequency which is neutralized, however, by the coupling from point X through switch s^7 40 and condensers C^9 , C^6 and inductance L^3 , with the result that such smaller proportion of the energy of undesired frequency previously present in the inductance L^3 is 45 eliminated and the current now traversing the driver coil D is purely of signal frequency, with the result that the effects of static are more completely eliminated from the instrument T .

In the foregoing description of the operation of Fig. 6, and in the description of the operation of Figs. 1 to 5 inclusive, there has been assumed to be transmitted from the distant co-operating transmitting station undamped waves modulated in accordance 55 with sound waves, as for telephony, or decadic wave trains for telegraphy. However, when the distant co-operating station is transmitting undamped waves for purposes of telegraphy, the telegraphic signals 60 may be rendered audible in the instrument T by heterodyne action, as by impressing upon the circuit of the grid g oscillatory energy locally produced and of a frequency differing from the signal frequency by an 65 amount to produce audible beats. H repre-

sents a source of high frequency oscillations, of frequency differing from the signal frequency, which may be impressed upon the grid circuit, upon closure of the switch s^{10} through oscillation transformer t . 70

It will be obvious also that when the arrangements of Figs. 1 to 5 inclusive are to be utilized for telegraphy employing undamped waves, a generator such as H may be coupled to the grid circuit of any of the 75 detector tubes V .

By opening the switches s^7 and s , or by entirely omitting the transformer P , S , all connections and apparatus below the point X^1 , including omission of the amplifier V^1 , 80 and by throwing the switch s^8 to the position indicated, and by opening switch s^{10} the source of high frequency sustained oscillations I is connected to the driver coil D , when it is desired to receive telegraphic 85 signals transmitted by undamped waves.

With the switches s^5 , s^6 and s^9 open, the antenna path is tuned to the signal frequency, as is also the circuit of the secondary S^2 . Switch s^9 is then closed, whereupon the antenna circuit is de-tuned with respect to the signal frequency, and then either of switches s^5 or s^6 is closed, and the condenser C^5 adjusted to neutralize the electro-motive-forces across the terminals of the 90 condenser C^{10} due to the oscillations of signal frequency and undesired frequency, and under these circumstances there is no effect upon the instrument T . Then by closing the switch s^8 with the source I operative, there 100 flows through the coil D sustained oscillations of a frequency differing at least from the signal frequency. By suitably adjusting the degree of coupling between D and F , and without regard to sense of coupling between D and F , the current in the coil D develops in the coil F an electro-motive-force 105 which prevents flow through the coil F of oscillations of signal frequency, in effect increasing the impedance of the coil F and compelling a greater proportion of the signal frequency to be transferred from primary P^2 to the circuit of the secondary S^2 , 110 thereby producing an effect upon the instrument T by the signal frequency and to some 115 extent by the energy of undesired frequency.

The frequency of the oscillations from the source I being different from the signal frequency, the signal energy controlling the instrument T rises and falls in amplitude at 120 audio frequency dependent upon the difference between the signal frequency and the frequency of the oscillations from source I . The amplitude of the current in F induced from the coil D is preferably made such as 125 to be equal to the amplitude of the signal oscillations in the coil F , with the result that the beat effect is a maximum because of substantial equality of the amplitudes of the reacting currents. The oscillations of unde- 130

sired frequency simultaneously existing in the coil F are generally of far greater amplitude, at least at the beginning of the wave train of undesired frequency, than the amplitude of the signal oscillations, with the result that only a small and unimportant beat effect results from the reaction of the currents induced in the coil D upon the currents of undesired frequency in the coil F, with the result that in the instrument T the beat effect due to the signal energy greatly predominates over the beat effect resulting from the oscillations due to static, and the telegraphic signals are readily distinguishable over the effects of static.

In the arrangement of Fig. 6 employing the source I in association with the coil D, the effects of static are at all times present in the instrument T. On the other hand, when the coil D is traversed by current from the amplifier V¹, when switch s⁷ is closed, and switch s closed or not, no effects of static can reach the telephone T during the spaces between telegraphic characters, it being assumed in this connection that the generator H is in operation and switch s¹⁰ closed.

For the sake of brevity in the appended claims, the term "signal" is employed generically to include signals of any character, including telegraphic and telephonic signals, and any other analogous effect, including controls; and the term "static" is generically employed to include static and other natural electrical effects and also other effects having artificial origin such as are caused or represented by waves or oscillations other than those representing the desired signal or control.

What I claim is:

40 1. The method of reducing the effect of static in reception of signals, which comprises receiving the signal oscillations in a path in which static oscillations occur, transferring static oscillations to a second path, applying to said second path an electro-motive-force derived from a point of elevated potential in said first named path to reduce the effect of said static oscillations, subjecting a signal circuit to an electro-motive-force derived from a point of elevated potential in said first named path, and translating into a signal the signal oscillations of said signal circuit.

55 2. The method of reducing the effect of static in reception of signals, which comprises receiving the signal oscillations in a path in which static oscillations occur, transferring static oscillations to a second path, applying to said second path an electro-motive-force derived from a point of elevated potential in said first named path to reduce the effect of said static oscillations, subjecting a signal circuit to an electro-motive-force derived from said point of elevated potential in said first named path, and

translating into a signal the signal oscillations of said signal circuit.

3. The method of reducing the effect of static in reception of signals, which comprises receiving the signal oscillations in a path in which static oscillations occur, de-tuning said path with respect to the frequency of the signal oscillations, transferring static oscillations to a second path attuned to the frequency of said static oscillations, applying to said second path an electro-motive-force derived from a point of elevated potential in said first named path to reduce the effect of said static oscillations, subjecting a signal circuit attuned to the frequency of the signal oscillations to an electro-motive-force derived from a point of elevated potential in said first named path, and translating into a signal the signal oscillations of said signal circuit.

4. The method of reducing the effect of static in reception of signals, which comprises receiving the signal oscillations in a path in which static oscillations occur, de-tuning said path with respect to the frequency of the signal oscillations, transferring static oscillations to a second path attuned to the frequency of said static oscillations, applying to said second path an electro-motive-force derived from a point of elevated potential in said first named path to reduce the effect of said static oscillations, subjecting a signal circuit attuned to the frequency of the signal oscillations to said point of elevated potential in said first named path, and translating into a signal the signal oscillations of said signal circuit.

5. The method of reducing the effect of static in reception of signals in a receiving system comprising a path in which occur signal and static oscillations, a path receiving static oscillations from said first named path, and a signal circuit coupled to said second path, which comprises impressing on said second path and said signal circuit electro-motive-forces from a region of elevated potential in said first named path to reduce the effect of static oscillations in said second path and to effect signal oscillations in said signal circuit, and translating into a signal the signal oscillations of said signal circuit.

6. The method of reducing the effect of static in reception of signals in a receiving system comprising a path in which occur signal and static oscillations, a path receiving static oscillations from said first named path, and a signal circuit coupled to said second path, which comprises de-tuning the said first named path with respect to the frequency of the signal oscillations, impressing upon said second path and said signal circuit electro-motive-forces from a region of elevated potential in said first named path to reduce the effect of static oscilla-

tions in said second path and to effect signal oscillations in said signal circuit, and translating into a signal the signal oscillations of said signal circuit.

- 5 7. The method of reducing the effect of static in reception of signals, which comprises receiving the signal oscillations in a path in which static oscillations occur, transferring static oscillations to a second path, 70
 10 applying to said second path an electro-motive-force derived from a point of elevated potential in said first named path to reduce the effect of said static oscillations, subjecting a signal circuit to an electro-motive- 75
 15 force derived from a point of elevated potential in said first named path, amplifying the signal oscillations of said signal circuit, varying the impedance of said first named path by said amplified oscillations, and 80
 20 translating the signal oscillations into a signal.

8. The method of reducing the effect of static in reception of signals, which comprises receiving the signal oscillations in a path in which static oscillations occur, de-tuning said path with respect to the frequency of the signal oscillations, transferring static oscillations to a second path, applying to said second path an electro-motive- 90
 25 force derived from a point of elevated potential in said first named path to reduce the effect of said static oscillations, influencing a signal circuit by the signal oscillations in said first named path, amplifying the signal oscillations of said signal circuit, varying the impedance of said first named path by said amplified oscillations to give to said first named path a period corresponding substantially with the period of the 95
 30 signal oscillations, and translating the signal oscillations into a signal.

- 40 9. The method of reducing the effect of static in reception of signals, which comprises receiving the signal oscillations in a path in which static oscillations occur, transferring oscillations from said path to a circuit, applying to said circuit an electro-motive-force derived from a point of elevated potential in said path to reduce the effect of the oscillations in said circuit, subjecting a signal circuit to an electro-motive-force derived from a point of elevated potential in said path, translating into a signal the oscillations of said signal circuit, applying to a third circuit an electro-motive-force of signal frequency derived from a point of elevated potential in said path, amplifying the oscillations of signal frequency of said third circuit, and controlling the aforesaid transfer of oscillations from said path into said first circuit by said amplified oscillations. 100
 45 10. The method of reducing the effect of static in reception of signals, which comprises receiving the signal oscillations in a path in which static oscillations occur, transferring oscillations from said path to a circuit, applying to said circuit an electro-motive-force derived from a point of elevated potential in said path to reduce the effect of the oscillations in said circuit, subjecting a signal circuit to an electro-motive-force derived from a point of elevated potential in said path, translating into a signal the oscillations of said signal circuit, applying to a third circuit an electro-motive-force of signal frequency derived from a point of elevated potential in said path, amplifying the oscillations of signal frequency of said third circuit, transferring from said path to a fourth circuit oscilla- 110

path in which static oscillations occur, transferring oscillations from said path to a circuit, applying to said circuit an electro-motive-force derived from a point of elevated potential in said path to reduce the effect of the oscillations in said circuit, subjecting a signal circuit to an electro-motive-force derived from a point of elevated potential in said path, translating into a signal the oscillations of said signal circuit, applying to a third circuit an electro-motive-force of signal frequency derived from a point of elevated potential in said path, amplifying the oscillations of signal frequency of said third circuit, transferring from said path to a fourth circuit oscillations of static frequency, applying to said fourth circuit an electro-motive-force from a point of elevated potential in said path for reducing the effect of the oscillations of static frequency of said fourth circuit upon said third circuit, and controlling the transfer of oscillations from said path to said third circuit by said amplified oscillations. 85

11. The method of reducing the effect of static in reception of signals, which comprises receiving the signal oscillations in a path in which static oscillations occur, transferring oscillations from said path to a circuit, applying to said circuit an electro-motive-force derived from a point of elevated potential in said path to reduce the effect of the oscillations in said circuit, subjecting a signal circuit to a point of elevated potential in said path, translating into a signal the oscillations of said signal circuit, applying to a third circuit an electro-motive-force of signal frequency derived from a point of elevated potential in said path, amplifying the oscillations of signal frequency of said third circuit, controlling the aforesaid transfer of oscillations from said path into said first circuit by said amplified oscillations, and causing locally produced oscillations to react with the signal oscillations to produce an audible signal. 100

tions of static frequency, applying to said fourth circuit an electro-motive-force from a point of elevated potential in said path for reducing the effect of the oscillations of static frequency of said fourth circuit upon said third circuit, controlling the transfer of oscillations from said path to said third circuit by said amplified oscillations, and causing locally produced oscillations to react with the signal oscillations to produce an audible signal.

13. The method of reducing the effect of static in reception of signals, which comprises receiving the signal oscillations in a path in which static oscillations occur, transmitting oscillations from said path to a circuit, applying to said circuit an electro-motive-force derived from a point of elevated potential in said path to reduce the effect of said oscillations in said circuit, subjecting a signal circuit to an electro-motive-force derived from a point of elevated potential in said path, translating into a signal the oscillations of said signal circuit, independently generating oscillations of a frequency differing from said signal oscillations, and controlling said transfer of oscillations from said path to said first named circuit by said locally generated oscillations.

14. A receiving system comprising a path traversed by signal and static oscillations and detuned with respect to the signal oscillations, a second path, a coupling between said paths, a coupling from a point of elevated potential in said first named path to said second named path, a signal circuit coupled to said first named path independently of said first named coupling, and a translating instrument controlled by said signal circuit.

15. A receiving system comprising a path traversed by signal and static oscillations and detuned with respect to the signal oscillations, a second path, a coupling between said paths, a coupling connection between said second path and a point of elevated potential in said first named path, a capacity in said coupling connection, a signal circuit affected by said first named path, and a translating instrument controlled by said signal circuit.

16. A receiving system comprising a path traversed by signal and static oscillations and detuned with respect to the signal oscillations, a second path, a coupling between said paths, a coupling connection between said second path and a point of elevated potential in said first named path, a signal circuit coupled to said first named path through said coupling connection, and a translating instrument controlled by said signal circuit.

17. A receiving system comprising a path traversed by signal and static oscillations and detuned with respect to the signal oscil-

lations, a second path, a coupling between said paths, a coupling connection between said second path and a point of elevated potential in said first named path, a signal circuit coupled to said first named path through said coupling connection, a capacity in said coupling connection, and a translating instrument controlled by said signal circuit.

18. A receiving system comprising a path traversed by signal and static oscillations, a second path, a circuit coupled to said paths, a signal circuit, means coupling said circuits to each other, means coupling said circuits to a region of elevated potential in said first named path, and a translating instrument controlled by said signal circuit.

19. A receiving system comprising a path transversed by signal and static oscillations, a second path, a circuit coupled to said paths, a signal circuit, means coupling said circuits to each other, a connection coupling said circuits to a point of elevated potential in said first named path, and a translating instrument controlled by said signal circuit.

20. A receiving system comprising a path traversed by signal and static oscillations, a second path, a circuit coupled to said paths, a signal circuit, means coupling said circuits to each other, means coupling said circuits to a region of elevated potential in said first named path, a capacity in said coupling connection, and a translating instrument controlled by said signal circuit.

21. A receiving system comprising a path traversed by signal and static oscillations, a second path, a circuit coupled to said paths, a signal circuit, means common to said circuits coupling them, means coupling said circuits to a region of elevated potential in said first named path, and a translating instrument controlled by said signal circuit.

22. A receiving system comprising a path traversed by signal and static oscillations, a second path, a circuit coupled to said paths, a signal circuit, means common to said circuits coupling them, a connection coupling said circuits to a point of elevated potential in said first named path, and a translating instrument controlled by said signal circuit.

23. A receiving system comprising a path traversed by signal and static oscillations, a second path, a circuit coupled to said paths, a signal circuit, means common to said circuits coupling them, means coupling said circuits to a region of elevated potential in said first named path, a capacity in said coupling connection, and a translating instrument controlled by said signaling circuit.

24. A receiving system comprising a path traversed by signal and static oscillations, a second path, a coupling between said paths, a coupling from a point of elevated potential in said first named path to said second named path, a signal circuit coupled to said

first named path independently of said first named coupling, means controlled by said signal circuit for amplifying the signal oscillations, means whereby the amplified oscillations affect said first named path, and a translating instrument controlled by said signal circuit.

25. A receiving system comprising a path traversed by signal and static oscillations, 10 a second path, a coupling between said paths, a coupling from a point of elevated potential in said first named path to said second named path, a signal circuit coupled to said first named path independently of 15 said first named coupling, inductances in parallel with each other in said first named path, means controlled by said signal circuit for amplifying the signal oscillations, a winding inductively related to one of said 20 inductances and traversed by the amplified oscillations, and a signal-translating instrument controlled by said signal circuit.

26. A receiving system comprising a path traversed by signal and static oscillations, a 25 second path, a coupling between said paths, a coupling from a point of elevated potential in said first named path to said second named path, a signal circuit coupled to said first named path independently of said first 30 named coupling, inductances in parallel with each other in said first named path, one of said inductances having small inductance compared with another of said inductances, means controlled by said signal circuit for amplifying the signal oscillations, a winding inductively related to said one of 35 said inductances of small value and traversed by the amplified oscillations, and a signal-translating instrument controlled by 40 said signal circuit.

27. A receiving system comprising a path traversed by signal and static oscillations, inductances in parallel with each other in said path, a signal circuit associated with 45 said first named path, means controlled by said signal circuit for amplifying the signal oscillations, means for varying the effective impedance of said inductances by the amplified oscillations, and a translating instrument 50 controlled by said signal circuit.

28. A receiving system comprising a path traversed by signal and static oscillations, a circuit, a coupling between said path and circuit, a coupling from a point of elevated 55 potential in said path to said circuit for reducing the effect of the oscillations in said circuit, a signal circuit coupled to said path independently of said first named coupling, a translating instrument controlled by said 60 signal circuit, a third circuit tuned to the signal frequency, a coupling between said third circuit and said path independent of said first named coupling, means for amplifying the oscillations of signal frequency of 65 said third circuit, and means controlled by

the amplified oscillations for controlling the transfer of oscillations from said path to said first named circuit.

29. A receiving system comprising a path traversed by signal and static oscillations, a 70 circuit, a coupling between said path and circuit, a coupling from a point of elevated potential in said path to said circuit for reducing the effect of the oscillations in said circuit, a signal circuit coupled to said path 75 independently of said first named coupling, a translating instrument controlled by said signal circuit, a third circuit tuned to the signal frequency, a coupling between said third circuit and said path independent of 80 said first named coupling, means for amplifying the oscillations of signal frequency of said third circuit, means controlled by the amplified oscillations for controlling the transfer of oscillations from said path to 85 said first named circuit, a fourth circuit tuned to the static oscillations, means coupling said fourth circuit to said path, and a coupling from a point of elevated potential 90 in said path to said fourth circuit for reducing the effect of the oscillations therein upon said third circuit.

30. A receiving system comprising a path traversed by signal and static oscillations, a 95 circuit, a coupling between said path and circuit, a coupling from a point of elevated potential in said path to said circuit for reducing the effect of the oscillations in said circuit, a signal circuit coupled to said path independently of said first named coupling, 100 a translating instrument controlled by said signal circuit, a third circuit tuned to the signal frequency, a coupling between said third circuit and said path independent of said first named coupling, means for amplifying the oscillations of signal frequency of 105 said third circuit, means controlled by the amplified oscillations for controlling the transfer of oscillations from said path to said first named circuit, a local source of 110 oscillations, and means for causing said oscillations to react with the oscillations of signal frequency to produce audible beats in said translating instrument.

31. A receiving system comprising a path 115 traversed by signal and static oscillations, a circuit, a coupling between said path and circuit, a coupling from a point of elevated potential in said path to said circuit for reducing the effect of the oscillations in said circuit, a signal circuit coupled to said path 120 independently of said first named coupling, a translating instrument controlled by said signal circuit, a third circuit tuned to the signal frequency, a coupling between said 125 third circuit and said path independent of said first named coupling, means for amplifying the oscillations of signal frequency of said third circuit, means controlled by the amplified oscillations for controlling the 130

transfer of oscillations from said path to said first named circuit, a fourth circuit tuned to the static oscillations, means coupling said fourth circuit to said path, a coupling from a point of elevated potential in said path to said fourth circuit for reducing the effect of the oscillations therein upon said third circuit, a local source of oscillations, and means for causing said oscillations to react with the oscillations of signal frequency to produce audible beats in said translating instrument.

32. A receiving system comprising a path traversed by signal and static oscillations, a circuit, a coupling between said path and circuit, a signal circuit, a translating instrument controlled by said signal circuit, a coupling from a point of elevated potential in said path to said first named circuit for reducing the effect of the oscillations upon said signal circuit, a local source of oscillations of a frequency different from the frequency of the signal oscillations, and means controlled by the oscillations from said local source controlling the transfer of oscillations from said path to said first named circuit through said first named coupling.

33. The method of reducing the effect of static in reception of signals, which comprises receiving the signal oscillations in a path detuned to the signal frequency and in which occur static oscillations of frequency different from the signal frequency, subjecting a second path tuned to the signal frequency to the signal oscillations in said first named path, subjecting a third path tuned to the static oscillations to the static oscillations in said first named path, and reducing the effect of static oscillations upon said second named path by static oscillations in said third named path.

34. The method of reducing the effect of static in reception of signals, which comprises receiving the signal oscillations in a path detuned to the signal frequency and in which occur static oscillations of frequency different from the signal frequency, subjecting a second path tuned to the signal frequency to the signal oscillations in said first named path, subjecting a third path tuned to the static oscillations to the static oscillations in said first named path, reducing the effect of static oscillations upon said second named path by static oscillations in said third named path, and utilizing local energy in the form of oscillations for changing the natural period of said first named path.

35. The method of reducing the effect of static in reception of signals, which comprises receiving the signal oscillations in a path detuned to the signal frequency and in which occur static oscillations of frequency different from the signal frequency, subjecting a second path tuned to the sig-

nal frequency to the signal oscillations in said first named path, subjecting a third path tuned to the static oscillations to the static oscillations in said first named path, reducing the effect of static oscillations upon said second named path by static oscillations in said third named path, and utilizing local energy in the form of oscillations for changing the natural period of said first named path to accord with the period of the signal oscillations.

36. The method of reducing the effect of static in reception of signals, which comprises receiving the signal oscillations in a path detuned to the signal frequency and in which occur static oscillations of frequency different from the signal frequency, subjecting a second path tuned to the signal frequency to the signal oscillations in said first named path, subjecting a third path tuned to the static oscillations to the static oscillations in said first named path, reducing the effect of static oscillations upon said second named path by static oscillations in said third named path, amplifying signal oscillations, and utilizing the amplified oscillations for changing the natural period of said first named path in a sense to approach the period of the signal oscillations.

37. The method of reducing the effect of static in reception of signals, which comprises receiving the signal oscillations in a path detuned to the signal frequency and in which static oscillations occur, subjecting a second path to an electro-motive-force derived from a point of elevated potential in said first named path for effecting oscillations of signal frequency in said second path, transferring static oscillations from said first named path to a third path, and applying to said third path an electro-motive-force derived from a point of elevated potential in said first named path to reduce the effect of said static oscillations upon said second named path.

38. The method of reducing the effect of static in reception of signals, which comprises receiving the signal oscillations in a path detuned to the signal frequency and in which static oscillations occur, subjecting a second path to an electro-motive-force derived from a point of elevated potential in said first named path for effecting oscillations of signal frequency in said second path, transferring static oscillations from said first named path to a third path, applying to said third path an electro-motive-force derived from a point of elevated potential in said first named path to reduce the effect of said static oscillations upon said second named path, and utilizing local energy in the form of oscillations for changing the natural period of said first named path.

39. The method of reducing the effect of static in reception of signals, which comprises receiving the signal oscillations in a path detuned to the signal frequency and in which static oscillations occur, subjecting a second path to an electro-motive-force derived from a point of elevated potential in said first named path for effecting oscillations of signal frequency in said second path, transferring static oscillations from said first named path to a third path, applying to said third path an electro-motive-force derived from a point of elevated potential in said first named path to reduce the effect of said static oscillations upon said second named path, amplifying signal oscillations, and utilizing the amplified oscillations for changing the natural period of said first named path in a sense to approach the period of the signal oscillations. 5 70
40. In the reception of radio signals, the method which comprises receiving the signal energy in a path detuned with respect thereto, and changing the natural period of said path by the effect of oscillations produced by local energy. 10 80
41. In the reception of radio signals, the method which comprises receiving the signal energy in a path detuned with respect thereto, and changing the natural period of said path in a sense to approach the period of the signal waves by the effect of oscillations produced by local energy. 15 85
42. In the reception of radio signals, the method which comprises receiving the signal energy in a path detuned with respect thereto, amplifying the signal oscillations, and utilizing the amplified oscillations for changing the natural period of said path. 20 90
43. In the reception of radio signals, the method which comprises receiving the signal energy in a path detuned with respect thereto, amplifying the signal oscillations, and utilizing the amplified oscillations for changing the natural period of said path in a sense to approach the period of the signal-representing oscillations. 25 95
44. In the reception of radio signals, the method which comprises receiving the signal energy in a path detuned with respect thereto, influencing a signal-translating circuit in opposite senses by the oscillations in said detuned path, whereby the effect upon said signal-translating circuit is substantially nil, and increasing the absorption of signal energy from said path by said signal-translating circuit by influencing said path by oscillations produced by local energy to substantially tune said path to the frequency of the signal oscillations. 30 100
45. In the reception of radio signals, the method which comprises receiving the signal energy in a path detuned with respect thereto, influencing a signal-translating circuit in opposite senses by the oscillations in said 35 115
46. A receiving system comprising a path traversed by signal and static oscillations, a path for signal oscillations, a third path detuned with respect to the signal oscillations, and means including a plurality of couplings for coupling said third path to said first named path in opposite senses for reducing the effect of static oscillations upon said path for signal oscillations. 40 120
47. A receiving system comprising a path detuned with respect to the signal oscillations and traversed by signal and static oscillations, a path for signal oscillations, a third path having the same natural period as said first named path, and means for coupling said third path to said first named path in opposite senses for reducing the effect of static oscillations upon said path for signal oscillations. 45 125
48. A receiving system comprising a path detuned with respect to the signal oscillations and traversed by signal and static oscillations, a path for signal oscillations, a third path having the same natural period as said first named path, means for coupling said third path to said first named path in opposite senses for reducing the effect of static oscillations upon said path for signal oscillations, and means for influencing said first named path by oscillations whose energy is at least in part derived from a local source of energy for changing the natural period of said first named path. 50 130
49. A receiving system comprising a path detuned with respect to the signal oscillations and traversed by signal and static oscillations, a path for signal oscillations, a third path having the same natural period as said first named path, means for coupling said third path to said first named path in opposite senses for reducing the effect of static oscillations upon said path for signal oscillations, means for amplifying signal-representing oscillations, and means through which said amplified oscillations influence said first named path to change its natural period in a sense approaching the period of the signal-representing oscillations. 55 135
50. A receiving system comprising a path detuned with respect to the signal oscillations and traversed by signal and static oscillations, a path for oscillations of signal frequency, means for subjecting said path to an electro-motive-force derived from a point of elevated potential in said first named path, a third path, means coupling said third path to said first named path, and means for ap- 60 140

plying to said third path an electro-motive-force derived from a point of elevated potential in said first named path for preventing substantial effect upon said second named 5 path of static oscillations.

51. A receiving system comprising a path detuned with respect to the signal oscillations and traversed by signal and static oscillations, a path for oscillations of signal frequency, means for subjecting said path to an electro-motive-force derived from a point of elevated potential in said first named path, a third path, means coupling said third path to said first named path, means for applying 10 to said third path an electro-motive-force derived from a point of elevated potential in said first named path for preventing substantial effect upon said second named path of static oscillations, means for amplifying 15 oscillations of signal frequency, and means through which said amplified oscillations influence said first named path to change its natural period in a sense approaching the period of the signal-representing 20 oscillations.

52. A receiving system comprising a path detuned with respect to the signal oscillations and traversed by signal and static oscillations, and means for changing the natural period of said path comprising means 30 for influencing said path by local oscillations.

53. A receiving system comprising a path detuned with respect to the signal oscillations and traversed by signal and static oscillations, means for amplifying oscillations of signal frequency, and means through 35 which the amplified oscillations influence said path to change its natural period in a sense approaching the period of the signal-representing oscillations.

54. A receiving system comprising a path including inductances in parallel with each other and detuned with respect to the signal 45 oscillations and traversed by signal and static oscillations, and means for influencing one of said inductances by local oscillations to change the natural period of said path.

55. A receiving system comprising a path 50 including inductances in parallel with each other and detuned with respect to the signal oscillations and traversed by signal and static oscillations, means for amplifying oscillations of signal frequency, and means for influencing one of said inductances by the 55 amplified oscillations for changing the natural period of said path in a sense approaching the period of the signal oscillations.

56. A receiving system comprising a path 60 detuned with respect to the signal oscillations and traversed by signal and static oscillations, a signal-translating circuit, means for influencing said signal-translating circuit in opposite senses by the oscillations in 65 said detuned path to render their influence

upon said circuit substantially nil, and means for increasing the absorption of the energy of signal oscillations by said signal-translating circuit from said path comprising means for influencing said path by local oscillations to change its natural period in a sense approaching the period of the signal oscillations. 70

57. A receiving system comprising a path 75 detuned with respect to the signal oscillations and traversed by signal and static oscillations, a signal-translating circuit, means for influencing said signal-translating circuit in opposite senses by the oscillations in said detuned path to render their influence upon said circuit substantially nil, and means for increasing the absorption of the energy of signal oscillations by said signal-translating circuit from said path comprising means for amplifying signal oscillations, and means for influencing said path by the amplified oscillations to change its natural period in a sense approaching the period of the signal oscillations. 80

58. A receiving system comprising a path 85 detuned with respect to the signal oscillations and traversed by signal and static oscillations, a signal-translating circuit, means for influencing said signal-translating circuit in opposite senses by the oscillations in 90 said detuned path to render their influence upon said circuit substantially nil, and means for increasing the absorption of the energy of signal oscillations by said signal-translating circuit from said path comprising a circuit for absorbing oscillations of signal frequency from said path, a third circuit, means for coupling said third circuit in opposite senses to said path for reducing the effect of static oscillations upon said 95 second named circuit, means for amplifying the signal oscillations absorbed in said second named circuit, and means for influencing said path by the amplified oscillations for changing the natural period of said path 100 in a sense approaching the period of the signal oscillations. 105

59. The method of reducing the effect of static in reception of signals, which comprises receiving the signal oscillations in a 115 path detuned to the signal frequency and in which occur static oscillations of frequency different from the frequency of the signal oscillations, subjecting a second path in opposite senses to the static oscillations in said 120 first named path for producing in said second path a point of substantially zero potential with respect to static oscillations, and transferring signal oscillations from said first named path to a third path through 125 said point of substantially zero potential.

60. The method of reducing the effect of static in reception of signals, which comprises receiving the signal oscillations in a 130 path detuned to the signal frequency and in

- which occur static oscillations of frequency different from the frequency of the signal oscillations, subjecting a second path tuned to the static oscillations in opposite senses to 5 the static oscillations in said first named path for producing in said second path a point of substantially zero potential with respect to the static oscillations, transferring signal oscillations from said first named 10 path to a third path tuned to the signal oscillations through said point of substantially zero potential, and utilizing local energy in the form of oscillations for changing the natural period of said first named path.
- 15 61. The method of reducing the effect of static in reception of signals, which comprises receiving the signal oscillations in a path detuned to the signal frequency and in which occur static oscillations of frequency 20 different from the frequency of the signal oscillations, subjecting a second path tuned to the static oscillations in opposite senses to the static oscillations in said first named path for producing in said second path a point of substantially zero potential with respect to static oscillations, transferring signal oscillations from said first named path to a third path tuned to the signal oscillations through said point of substantially zero 25 potential, amplifying signal oscillations, and utilizing the amplified oscillations for changing the natural period of said first named path.
- 30 62. A receiving system comprising a path 35 traversed by signal and static oscillations and having a natural period which is shorter
- than the period of the signal oscillations, and means for increasing the natural period of said path comprising means for influencing said path by oscillations whose energy 40 is at least in substantial proportion represented by local energy.
63. A receiving system comprising a path traversed by signal and static oscillations and having a natural period which is shorter 45 than the period of the signal oscillations, means for amplifying received oscillations of signal frequency, and means through which the amplified oscillations influence said path to increase its natural period.
- 50 64. A receiving system comprising a path including inductances in parallel with each other and traversed by signal and static oscillations and having a natural period shorter than the period of the signal oscillations, and means for influencing one of said inductances by local oscillations to increase 55 the natural period of said path.
65. A receiving system comprising a path including inductances in parallel with each other and traversed by signal and static oscillations and having a natural period shorter than the period of the signal oscillations, means for amplifying received oscillations of signal frequency, and means for 60 influencing one of said inductances by the amplified oscillations for increasing the natural period of said path.

In testimony whereof I have hereunto affixed my signature this 10th day of July, 70
1923.

DAVID G. McCAA.
